UNITED STATES PATENT OFFICE.

CASWELL V. HAYS, OF DILLON, SOUTH CAROLINA.

TABLET.

1,343,778.

Specification of Letters Patent. Patented June 15, 1920.

Application filed February 12, 1919. Serial No. 276,535.

To all whom it may concern:

Be it known that I, CASWELL V. HAYS, a citizen of the United States of America, residing at Dillon, in the county of Dillon and State of South Carolina, have invented new and useful Improvements in Tablets, of which the following is a specification.

The object of the invention is to provide a cheap and neat pencil and pen holding attachment for use in conjunction with tablets and books. In illustrating a specific form thereof is adhered to, but to this form the invention is not to be restricted. The right is reserved to make such changes or alterations as the actual reduction to practice may suggest, in so far as such changes or alterations are compatible in spirit with the annexed claim.

In the accompanying drawings:

Figure 1 is a perspective view of a tablet embodying the invention.

Fig. 2 is a section on the line 2—2 of Fig. 1.

Referring to the drawings, there is shown a tablet comprising a stiffening back 1 on which are attached a plurality of superposed sheets 2. The stiffening back 1 is increased in length over the sheets a sufficient amount to permit the placement on the stiffening back adjacent the upper end of preferably paste board box 3 whose length is the width of the tablet and whose height is equal to the combined thickness of the superposed sheets. A binding 4 is glued or otherwise suitably

attached on the stiffening back on the rear 35 face thereof carried around and secured in the same manner to one side of box 3 and then folded onto and secured in the same way on the outer face of a cover flap 5, the latter being adapted for turning down 40 against the uppermost sheet 2 when it acts as a closure member for the box 3, or thrown back to expose the uppermost sheet 2 and leave the box 3 open, the box being open on that face lying in the plane of the uppermost 45 sheet 2.

It will be observed that the box 3 provides a convenient case or keeper for a pen or pencil, and when the cover flap 5 is down against the tablet, it serves to keep the pen 50 or pencil in place.

The invention having been described, what is claimed as new and useful is:

As a new article of manufacture, the combination with a stiffening back and a plurality of superposed sheets mounted thereon, of a box secured to the said back and against one end of the superposed sheets, the box being open on that face lying in the plane of the uppermost sheet, and a cover flap having 55 means for securing it to the back and to the box, whereby the cover flap may be folded down against the uppermost sheet to close the box or thrown back to expose the sheet and open the box, the box being adapted to 60 receive a pen or pencil.

In testimony whereof I affix my signature.
CASWELL V. HAYS.
